(57) **CLAIM**

The ornamental design for a toggle switch guard, as shown and described.

DESCRIPTION

FIG. 1 is a top isometric view of a portion of a toggle switch guard showing my new design.

FIG. 2 is a left side elevational view thereof.

FIG. 3 is a right side elevational view thereof.

FIG. 4 is a top plan view thereof.

FIG. 5 is a bottom plan view thereof.

FIG. 6 is a front elevational view thereof.

FIG. 7 is a back elevational view thereof; and,

FIG. 8 is an isometric view thereof with a section cut away taken along line 8-8 in FIG. 6.

The broken lines in the drawings depict environmental structure associated with the toggle switch guard that form no part of the claimed design.
